UNITED STATES PATENT OFFICE.

ANDREW W. AITKEN, OF SPRINGFIELD, OHIO, ASSIGNOR TO THE BUFFALO-SPRINGFIELD ROLLER COMPANY, OF SPRINGFIELD, OHIO, A CORPORATION OF OHIO.

FRAME STRUCTURE FOR ROAD ROLLERS.

Application filed November 21, 1921, Serial No. 516,574. Renewed January 11, 1923.

To all whom it may concern:

Be it known that I, ANDREW W. AITKEN, a citizen of the United States, residing at Springfield, in the county of Clark and State 5 of Ohio, have invented certain new and useful Improvements in Frame Structures for Road Rollers, of which the following is a specification.

My invention relates to frame structures 10 for road rollers.

The object of my invention is to provide a structure of this character of such a nature as will provide a substantial support for the water tank and also a rigid point of attachment 15 for a draw-bar and at the same time be so arranged as to permit the ready removal of the rear axle when desired.

In the accompanying drawings:—

Figs. 1 and 3 represent, when placed together end to end, a top plan view of the structure.

Figs. 2 and 4, when placed together end to end, represent a side elevation of the same.

Fig. 5 is an enlarged vertical sectional view 25 on the line 5—5 of Fig. 1.

Fig. 6 is an enlarged vertical section on the line 6—6 of Fig. 1.

Referring to the drawings, 1 and 2 represent steel vertically-disposed side plate members, the forward ends of which are projected upwardly and forwardly and carry the head 3 in which is journaled in the usual way the swivelled king post for the forward roller. The upper edge of each of these 35 plates is reinforced by an angle-iron 4, these angle irons being tied together by the bars 5. Riveted to the lower edge of each of these side plates is a channel beam, 6 and 7, these beams being tied together by the channel 40 bars 8 and 9; the bars and the beams being connected together by the angle irons 10. Each of the side plates 1 and 2 has an opening 11 to receive the bearing for the rear axle these openings being within a short distance 45 of the rear edges of the respective plates, each plate being slotted between the opening and its rear edge as indicated at 11^a whereby the axle may be removed when desired.

50 The channel beams 6 and 7 are extended rearwardly beyond the rear edges of the plates 1 and 2 and have bolted to their rear ends, through the angle irons 12, the water tank 13. The sides 13^a of the water tank are 55 extended beyond the front wall thereof, as

indicated at 13^b, and these extended edges are bolted to the rear ends of the side plates 1 and 2 by bolts 14; a stiffening bar 15 being inserted between the heads of the bolts and the extended portions of the tank.

A draw bar 16 of any suitable form is attached to the rear ends of the beams 6 and 7 by the angle irons 17, this draw bar being of a nature to receive the draft appliances of scarifying devices, or to which may be hitched any other structure designed to be drawn by the roller.

By the construction described it will be seen that a frame structure is provided which will be of ample rigidity and strength 70 to not only support the operating parts of the roller and the water tank thereof, but also provides a rigid point of attachment for draft appliances so that the tank may be relieved of the strain which would be otherwise impressed upon it by the attachment of such appliances directly thereto as has been the custom. It will be seen that in the event it is desired to remove the rear axle, this 75 can be accomplished readily by removing the tank and then the axle through the slotted 80 openings.

Having thus described my invention, I claim:—

1. In a frame structure of the character 85 described, a pair of vertically disposed side plates, a pair of side beams connected therewith, said plates having openings to receive the rear axle, the beams being extended rearwardly beyond the plates, a tank removably supported from the beams and also removably connected with the rear edges of 90 said plates, provision for the attachment of draft appliances to the rear ends of said beams, and means whereby the axle may be 95 removed from said plates when said tank is removed.

2. In a frame structure of the character 100 described, a pair of braced vertically-disposed side plates having openings to receive the rear axle with slots leading from the openings to the rear edges of said plates, channel beams connected to the lower edges of said plates and projecting rearwardly 105 therefrom, and a tank removably secured to the rear edges of said plates and also removably connected with the beams at points beyond the rear edges of the plates, the rear ends of said beams having provision for the attachment of draft appliances. 110

3. In a frame structure of the character described, a pair of vertically-disposed side plates, each having an opening to receive the rear axle with a slot leading from the opening to the rear edge of the plate, an angle iron secured to the top edge of each plate, tie rods for securing said angle irons together, a channel beam connected to the lower edge of each plate and projecting rearwardly therefrom, and a tank removably secured to the rear edges of said plates and also removably connected with the beams at points beyond the rear edges of the plates.
4. In a frame structure of the character described, a pair of vertically-disposed side plates, each having an opening to receive the rear axle and a slot leading from the opening to the rear edge thereof, bars for tying the upper edges of said plates together, a channel beam secured to the lower edge of each plate and projecting rearwardly therefrom, a tank having forwardly projecting flanges, connections for securing said flanges to the rear edges of said plates including reinforcing members, and means for removably securing said tank to said beams.

5. In a frame structure of the character described, a pair of vertically-disposed side plates, a pair of side beams connected therewith, said plates having openings to receive the rear axle, the beams being extended rearwardly beyond the plates, a tank removably supported from the beams and extending to within close proximity to the rear ends of said plates, provision for attachment of draft appliances to the rear ends of said beams, and means whereby the axle may be removed from said plates when said tank is removed.
6. In a frame structure of the character described, a pair of vertically-disposed side plates, a pair of side beams connected therewith, said plates having openings to receive the rear axle, the beams being extended rearwardly beyond the plates, a tank removably connected with the rear edges of said plates, provision for the attachment of draft appliances to the rear ends of said beams, and means whereby the axle may be removed from said plates when said tank is removed.

In testimony whereof, I have hereunto set my hand this 15th day of November 1921.

ANDREW W. AITKEN.
